MODULATION SYSTEM

Newsome Henry Cleugh, Brentwood, England, assignor to Radio Corporation of America, a corporation of Delaware

Application May 6, 1939, Serial No. 272,076
In Great Britain April 22, 1938

7 Claims. (Cl. 179—171.5)

This invention relates to modulator circuit arrangements and has for its object to provide improved modulator circuit arrangements of high efficiency, comparative simplicity and cheapness, and comparative immunity from those known leakage resonance and similar disadvantageous effects which occur in known high efficiency modulator systems involving the use of relatively large iron cored transformers.

According to this invention in its broadest aspect a modulator system comprises two so-called class C high frequency stages fed in series from a direct current source with a low frequency choke between said stages and four so-called class B modulator tubes so connected as to constitute alternative valve paths from the D. C. source to each stage, two of the modulator tubes operating to secure modulation for positive half waves and the other two operating to secure modulation for negative half waves, the whole arrangement being such that in effect the high frequency stages are made to take power in parallel from the direct current source at the peaks of modulation.

The invention is illustrated in and further explained in connection with the accompanying drawings.

In the drawings Fig. 1 illustrates somewhat diagrammatically my modulation system wherein two class C stages are connected in series by a choke coil and the stages are per se shunted by modulator tubes with each stage and the choke coil shunted by other modulator tubes, the modulator tubes operating class B and being modulated differentially in pairs to thereby modulate the potential on the high-frequency stages and, consequently, their ability to convert direct current to alternating current power.

Figs. 2 to 5, inclusive, are modifications of the arrangement of Fig. 1. In Fig. 2, which is substantially similar to Fig. 1, the modulating circuits are shown and include means for applying more modulating potentials to a pair of the modulator tubes than to another pair. In Fig. 3 a pair of the modulator tubes have their input electrodes excited by the outputs of the other modulator tubes. In Fig. 4 the modulating potentials are applied in somewhat the same manner in which they will apply in Fig. 3. In Fig. 4, however, radio-frequency chokes are interposed between the high frequency stages and the modulation potential choke. In Fig. 5 the modulating potentials are applied through sub-modulators.

In order that the invention may be the better

understood there will first be described with reference to Figure 1 a highly simplified circuit which may be regarded as descriptive of the basic principle of the invention.

In the theoretical basic circuit of Figure 1 there is connected across a source HT of direct current potential, a series circuit consisting, in the order stated, of a class C high frequency amplifier stage HF¹, a low frequency choke CH, and a second class C high frequency amplifier stage HF². The side of the stage HF¹ adjacent the positive terminal of the source HT is marked A, the other side of said stage is marked B the remaining side of the choke CH is marked C and the side of the stage HF² adjacent the negative terminal of the source HT is marked D. A modulator tube V¹ has its anode connected to point B and its cathode connected to point D and a second modulator tube V² has its anode connected to point A and its cathode to point C. The tubes V¹ and V² operate in class B and are arranged to be conductive simultaneously on the same half cycle. In order to simplify Figure 1 the speech input circuits for the modulator tubes are not shown. The circuit constants are such that in the carrier condition the two high frequency stages HF¹ HF² contribute equally to a common output and the potentials between points A and B and points C and D are equal, the tubes V¹ and V² being at or a little above the cut-off point so that their "feeds" are very low. If now the control grids of V¹ and V² be simultaneously made less negative with respect to their respective filaments, the voltages between points B and D and points A and C will be simultaneously reduced, and the voltages between points A and B and points C and D, i. e. the voltages across the high frequency stages HF¹ and HF², will be simultaneously increased. In the limit, when the internal resistances of V¹ and V² become zero, the whole voltage of the source HT will be applied across each high frequency stage and the equivalent of peak 100% modulation will be obtained. In the basic circuit, as so far described, only the two modulator tubes V¹ V² are referred to, but two further correspondingly connected tubes V¹' V²' are provided to deal with the other half waves of modulation the two said further tubes being connected between points A and B and between points C and D respectively. It will usually be found desirable to connect the negative end of the source, or some other point thereon, or the centre point of the choke CH to earth.

In the above basic circuit it should be noted that as the four modulator tubes require the

same grid-filament modulation input, two of the tubes, $V1'$ and $V2$ whose filament-earth potential is not constant, being dependent on the modulation—will require different grid-earth input voltages from those required by the other two tubes $V1$ and $V2'$ whose filaments are either earthed or at constant potential with relation to earth. A practical circuit in which this fact is taken into account is shown in Figure 2 and comprises a direct current source HT , represented by two generators in series two high frequency stages $HF1$ $HF2$ operated in class C and a choke CH all connected as in the basic circuit, and four modulator tubes operated as before in class B and designated respectively $V1$, $V1'$, $V2$, $V2'$. Modulation input is applied by a transformer T having a secondary S with a centre tap ST through which bias potential may, if required, be applied or which may be connected directly to earth. One end of the transformer secondary is connected, if required through a negative bias source as shown, to the grid of the tube $V1'$ and the other end of the transformer secondary is connected, also through a bias source, if required to the grid of the tube $V2$. Intermediate taps $IT1$, $IT2$ on the transformer secondary symmetrically disposed with relation to the mid-point ST are connected, one, through a negative bias source if required to the grid of $V1$ and the other, through a similar negative bias source if required to the grid of $V2'$. The anodes of $V1'$ and $V2$ are connected to the positive terminal of the source HT and the cathodes of $V1$ and $V2'$ are connected at the negative terminal thereof. The cathode of $V2$ is connected to the anode of $V2'$ and to the point C . The cathode of $V1'$ is connected to the anode of $V1$ and to the point B .

It will be seen that with this circuit the grid of tube $V2$ must be moved in the positive direction by the amount by which the grid of tube $V1$ has been moved plus the amount by which the point C is moved, if the valves have equal characteristics and identical bias settings and the grid transformer taps are correctly disposed to achieve this result.

In the description as so far given, it has been assumed throughout that the points B and C at the ends of the choke are the only points of connection of the choke to the modulator tubes. This, however, is not a necessary feature and in order to ensure in a simple manner that the grid-filament potential of $V2$ shall move in the correct phase and amplitude relation with respect to that of $V1$ with minimum difficulty due to stray capacity effects the circuit now to be described with reference to Figure 3, may with advantage be adopted. In this circuit two class C high frequency stages $HF1$ and $HF2$ and a choke CH are connected as before across the direct current source HT . The choke CH , however, is provided with two intermediate taps B' and C' equidistant from B and C respectively. The grid of $V1'$ is connected through a negative bias source to B , and the cathode of $V1'$ is connected to B' ; the grid of $V2$ is connected through a negative bias source to C and the cathode of $V2$ to C' . The anode-cathode space of $V1$ is connected between B' and D and that of $V2'$ between C' and D . Speech or other modulated input is applied through a speech transformer T whose secondary S has its ends connected respectively to the grids of $V1$ and $V2'$, the mid-point of the secondary being connected through a negative bias source to the point D . In this arrangement the tube $V2$ and, of course, also the tube $V1'$ is controlled au-

tomatically by voltage set up in the choke CH . By properly choosing the location of the points B' C' a modulation depth of 100% is obtainable.

In another arrangement shown in Figure 4 a series circuit consisting in the order stated of a high frequency choke $HFC1$, a high frequency class C amplifier valve $HF1$, a second high frequency choke $HFC2$, a low frequency choke CH , a third high frequency choke $HFC3$, a fourth high frequency choke $HFC4$, and a second high frequency class C amplifier valve $HF2$ is connected between positive and negative terminals of a source HT of potential. The anode of the valve $HF1$ is connected through the choke $HFC1$ to the positive terminal of the source HT and the cathode of the valve $HF2$ is connected direct to the negative terminal of the said source. In shunt across the series circuit consisting of the choke $HFC2$ the choke CH and the choke $HFC3$ are two fixed condensers $K1$, $K2$. The anode of $HF1$ is capacity coupled by condenser $K3$ to one end and the anode of the tube $HF2$ is capacity coupled by condenser $K4$ to the other end of a parallel tuned circuit comprising an inductance L in parallel with the usual "three plate" condenser CP having in effect a mid-tap. The mid-tap of the tuning condenser is connected to the junction point between the two fixed condensers $K1$, $K2$, and the tuned circuit inductance L is coupled to the output coil $L1$. The low frequency choke CH is between the points B , C , and has a centre tap CHS which may be connected to earth if required, and intermediate taps B' C' equidistant respectively from B and C . The grid of a modulating tube $V1'$ is adjustably tapped upon a resistance $R1$ which is in series with a condenser $C1$ and a negative bias source $GB1$ between the point B on the one hand and the cathode of the tube $V1'$ on the other, one plate of the condenser $C1$ being connected to B . Similarly the grid of a tube $V2$ is adjustably tapped upon a resistance $R2$ which is in series with a condenser $C2$ and a negative bias source $GB2$ between C and the cathode of $V2$ one plate of the condenser $C2$ being connected to C . The tube $V1$ has its grid connected through a negative bias source to one end of the secondary S of a speech input transformer T and tube $V2'$ has its grid connected through a negative bias source to the other end of said secondary. The said secondary has a centre tap ST which is connected to the point D (this is the same as the negative terminal of the direct current potential source HT) through a negative bias source. The anodes of the tubes $V1'$ and $V2$ are connected to the point A (the positive terminal of the direct current source HT); the cathodes of the tubes $V1$ and $V2'$ are connected to the point D ; the anode of tube $V1$ is connected to the cathode of tube $V1'$ and to the point B' ; and the anode of the valve $V2'$ is connected to the cathode of valve $V2$ and to the point C' .

Figure 5 shows a further preferred modification in which, however, sub-modulator tubes $VS1$ and $VS2$ are employed, the grid potentials (both steady and varying) for the modulator tubes $V1'$ and $V2$ being obtained from across resistances $AR1$, $AR2$, in the anode circuits of the sub-modulators $VS1$ $VS2$ respectively. The grids of valves $VS1$ $VS2$ are driven in phase with, but usually carry smaller amplitudes than the grids of $V1'$ and $V2$ respectively, i. e. the grids of $VS1$ $VS2$ are driven in phase opposition. The drive may be obtained in any of a variety of ways. For example (this is not shown) speech input may be effected by means of a transformer having two

push-pull secondaries, one connected between the grids of V1 and V2' and the second connected between the grids of VS1 and VS2, the centre points of the two push-pull secondaries being connected respectively to the bias supplies required by V1 and V2' (on the one hand) and VS1 and VS2 (on the other). The particular sub-modulator circuit shown in Figure 5 forms per se no part of the present invention.

Alternatively, and as shown in Figure 5, potentiometers P1 P2 connected as shown, may be provided for adjusting the relative amplitude of the speech inputs to VS1 and VS2 on the one hand and to V1 V2' on the other, and speech input to VS1 VS2 V1 V2' be effected from sub-sub-modulator tubes VSS1 VSS2 (which are fed from the speech input transformer T) by resistance-capacity coupling effected by elements KRA1, KRA2, and KC1 KC2.

In certain of the figures batteries are shown as providing anode and grid bias voltages. For example in Figure 5 a battery is represented as supplying anode voltage to the sub-sub-modulators (VSS1 and VSS2) and grid bias to these tubes and to the sub-modulators (VS1 and VS2). Obviously any other suitable potential sources may be used with or without smoothing filters and/or potentiometer adjustment means as may be required.

It is not absolutely necessary that the outputs of the two high frequency stages be combined in a single circuit. For example, in a case where the same programme is required to be transmitted on two different wave lengths simultaneously, the two high frequency tubes may operate on different wave lengths with individual high frequency input drives and, of course, individual output circuits.

Having now particularly described and ascertained the nature of my said invention and in what manner the same is to be performed I declare that what I claim is:

1. In a modulation system, two class C high frequency amplifiers, a source of direct current potential, a modulation potential choke coil, a circuit connecting said high frequency amplifiers and said choke coil in series with the choke coil between said high frequency amplifiers, means connecting said series circuit in shunt to said direct current source, two pairs of electron discharge modulator systems each having electrodes between which impedance exists, means connecting the impedances of a pair of said electron discharge systems in series, means connecting the junction point between said last named series-connected impedances to a point on said choke coil, means connecting the said impedances of the other pair of said electron discharge systems in series, means connecting a point between the said last named series impedances to another point on said choke coil and means for modulating substantially in phase opposition the impedances of pairs of said systems at modulation potential frequency to modulate said high frequency stages on positive and negative half cycles of the modulation frequency.

2. A system as recited in claim 1 wherein said last named means includes means for modulating the impedances of a pair of said systems through a range greater than the range through which the impedances of another pair of said systems is modulated.

3. In a modulation system, two class C high frequency amplifier stages, a source of direct current potential, a choke coil having a point there-

5 on connected to one of said high frequency stages and a second point thereon connected to another of said high frequency stages to form with said high frequency stages a series circuit, means connecting said series circuit in shunt to said source of direct current potential, two pairs of electron discharge modulator tubes each having input electrodes and output impedances, means connecting one of the tubes of a pair of said tubes in shunt to one of said high frequency stages and the other of the tubes of said one pair of tubes in shunt to the other of said high frequency stages and said choke coil, means connecting one of the tubes of the other pair of said tubes in shunt to 10 one of said high frequency stages, means connecting the other of said tubes of said other pair of tubes in shunt to the other of said high frequency stages and said choke coil, and means for impressing modulating potentials substantially in phase opposition on the input electrodes of said pairs of tubes.

4. A system as recited in claim 3 wherein said last named means includes means for impressing modulating potentials on a tube of each pair of tubes of greater amplitude than the modulating potentials impressed on the other tube of each pair of tubes.

5. In a modulation system, two class C high frequency amplifier stages, a source of direct current potential, a choke coil having a point thereon connected to one of said high frequency stages and a second point thereon connected to another of said high frequency stages to form with said high frequency stages a series circuit, 20 means connecting said series circuit in shunt to said source of direct current potential, four electron discharge modulator tubes each having input electrodes and output impedances, an impedance connecting two of said electron discharge modulator tubes input electrodes in push-pull relation, means connecting points on said last named impedance to the input electrodes of the other two of said tubes to connect the input electrodes thereof in push-pull relation, means connecting one of said first two tubes in shunt to one of said high frequency stages and the other of said first two tubes in shunt to said one of said high frequency stages and said choke coil, means connecting one of said other two tubes in shunt to the other of said high frequency stages and the other of said other two tubes in shunt to 25 said last named high frequency stage and said choke coil and means for impressing modulating potentials on said impedance connecting the input electrodes of two of said tubes in push pull relation.

6. A system as recited in claim 5 wherein said four tubes have their input electrodes biassed for class B operation.

7. In a modulation system, two class C high frequency amplifier stages, a source of direct current potential, a choke coil having a point thereon connected to one of said high frequency stages and a second point thereon connected to another of said high frequency stages to form with said high frequency stages a series circuit, means connecting said series circuit in shunt to said source of direct current potential, two pairs of electron discharge modulator tubes each having input electrodes and output impedances, an impedance connecting two of the electron discharge modulator tubes input electrodes in push-pull relation, means connecting points on said choke coil to the input electrodes of the other two of said modulator tubes, means connecting one of

said first two of said tubes in shunt to one of said high frequency stages and the other of said first two tubes in shunt to said one of said high frequency stages and said choke coil, means connecting one of said other two tubes in shunt to the other of said high frequency stages and the other of said other two tubes in shunt to said

5 last named high frequency stage and said choke coil, and means for impressing modulating potentials on said impedance connecting the input electrodes of said first two tubes in push-pull relation.

NEWSOME HENRY CLOUGH.
